(57) **CLAIM**

The ornamental design for a thermal combination hot or cold cylindrical beverage glass, as shown and described.

DESCRIPTION

FIG. 1 is a side perspective view of a preferred embodiment of the thermal combination hot or cold cylindrical beverage glass, showing my design;

FIG. 2 is a front view thereof, the rear and two sides being mirror images;

FIG. 3 is a top view thereof; and,

FIG. 4 is a bottom view thereof.
